Amelia P. Dutton Jr.
by M. H. Steensel Jr.
Attorney.

UNITED STATES PATENT OFFICE.

AMELIA P. DUTTON, JR., OF WASHINGTON, DISTRICT OF COLUMBIA.

GARMENT.

Application filed April 26, 1923. Serial No. 634,825.

To all whom it may concern:

Be it known that I, AMELIA P. DUTTON, Jr., a citizen of the United States, residing at Washington, in the District of Columbia, 5 have invented a certain new and useful Improvement in Garments, of which the following is a full, clear, and exact description.

The present day styles in women's garments, particularly waists, blouses, and dresses of various kinds, demand sleeves of a long and loose design, or sleeves having trimmings of a trailing or pendant nature, and it has been found by experience that 15 although such sleeves are attractive in appearance, they possess, from a practical standpoint, disadvantages, in that they are constantly dragging over objects which they encounter upon movement of the wearer's 20 arms thereby becoming a cause of annoyance and irritation.

This dragging of the sleeves is particularly annoying during the playing of card and other games in that it tends to disarrange 25 the cards or other game pieces.

The object of my invention is to provide a garment sleeve, which, while possessing all of the length and looseness demanded by the styles, is, nevertheless, capable of being 30 shortened temporarily during the performance of various acts, such as the playing of games, without in any way detracting from its stylish appearance; this shortening tending to enhance the comfort and convenience 35 of the wearer.

To this end the invention consists in a body garment having sleeves adapted to be turned back or doubled upon themselves, and cooperating means on the sleeves and on 40 an adjacent portion of the garment for maintaining the sleeves in such turned-back position, as I will proceed now to explain and finally claim.

In the accompanying drawings illustrating the invention, in the several figures of which like parts are similarly designated, Figure 1 is a view of a blouse having sleeves embodying my invention, one of same being turned back. Fig. 2 is a fragmentary view 45 of one sleeve in full length position. Fig. 3 is a view similar to Fig. 2 but showing the sleeve turned back.

The garment illustrated is of more or less conventional Chinese design, although the 55 invention is not limited to such design, and comprises essentially a body portion 1 and

sleeves 2 having loose or flowing ends 3 slit or vented as at 4.

When the sleeves are in the position illustrated at the left of Fig. 1 and in Fig. 2, 60 they fall approximately to the wrist of the wearer in graceful flowing lines or drape, but when in this position they have the disadvantage, above mentioned, of dragging over objects, to the annoyance and incon- 65 venience of the wearer.

To avoid this inconvenience the sleeves may be turned back or doubled upon themselves, as shown at the right of Fig. 1 and in Fig. 3, and held in such position by co-operating means on the sleeve and shoulder, such as a loop 5 and button or the like 6, respectively. When in this position the end 7 of the slit or vent 4 lies under the armpit of the wearer and the lower edge 8 of the sleeve 75 drapes gracefully over her upper arm, as shown, the sleeve being in this manner shortened to approximately elbow length, and so retained.

As above pointed out, the blouse illustrated is of conventional Chinese design, and this effect is enhanced by a trimming of braid 9 and Chinese beads or tokens 10, and the members 6 also may be Chinese beads.

The beauty of the garment may be enhanced by a contrasting of colors, when the sleeves are turned back, by providing a sleeve lining of a color different from that of the sleeve itself; and the loop 5 may be supplemented by a decorative arrangement 80 of braid, as shown at 11.

It will thus be seen that I provide a garment well suited to the purpose for which it is designed, and withal sacrificing nothing of beauty to utility.

Obviously, in garments of a type or style with which the use of buttons or beads and loops at 6 and 5, respectively, would be incongruous or unsightly, snap fasteners or other so-called invisible fastening devices 100 might be substituted therefor; and other changes might be made in the style and formation of the garment without departing from the spirit of the invention or the scope of the following claims.

What I claim is:—

1. In a body garment, a sleeve adapted to be turned back upon itself, and cooperating means located adjacent to the lower edge of said sleeve and on the shoulder portion of 110 said garment respectively for maintaining said sleeve in turned-back position, the lower

portion of said sleeve when turned back draping over the upper arm of the wearer.

2. In a body garment, sleeves provided with vents at their lower portions and 5 adapted to be turned back upon themselves, and cooperating fastening means on the lower portions of said sleeves at points thereon opposite to said vents and on the shoulders of said garments respectively for 10 maintaining said sleeves in turned-back po-

sition, said vents adapted to underlie the armpits of the wearer and permit the lower portion of the sleeves to drape over the upper arm.

In testimony whereof I have hereunto set 15 my hand this 26th day of April, A. D., 1923.

AMELIA P. DUTTON, JR.
